UNITED STATES PATENT OFFICE.

CHARLES EBERLE AND JACOB F. SCHOELLKOPF, OF DALLAS, TEXAS.

HORSE-COLLAR.

1,087,934.

Specification of Letters Patent. Patented Feb. 24, 1914.

Application filed February 16, 1911. Serial No. 609,020.

To all whom it may concern:

Be it known that we, CHARLES EBERLE and JACOB F. SCHOELLKOPF, citizens of the United States, residing at Dallas, in the county of Dallas and State of Texas, have invented certain new and useful Improvements in Horse-Collars, of which the following is a specification.

Our invention relates to new and useful 10 improvements in horse collars, and relates more particularly to articles of this class, adapted for use in conjunction with large hames of wood or other material.

The object of the invention is to provide 15 a stronger and more serviceable horse collar than has heretofore been made, and one that will have a large hame room, or groove between the rim and the body of the collar, in which the hame will be securely held, preventing any possibility of its slipping off of 20 the collar.

Another object is to improve the seam, which unites the rim to the body of the collar, and to make the joint between these 25 parts more easily and quickly, and with less expense than has heretofore been done.

With these and various other objects in view, our invention has relation to certain 30 novel features of the construction and operation, an example of which is described in the following specification and illustrated in the accompanying drawing, wherein:

Figure 1 shows a cross-section through 35 the collar, and also shows a portion of the collar in perspective. Fig. 2 is a side view of a portion of the rim, showing how the rim is secured to the body by a novel form of joint, consisting in lacing and stitching a welt between the respective edges of the 40 body and rim, said edges meeting upon the welt. Fig. 3 is a view showing a portion of the seam, connecting the upper and lower strips, which form the body, at their outer edges, two different manners of lacing said 45 strips together being shown. Fig. 4 is a perspective view of a portion of the collar rim, illustrating a modification of the construction shown in Fig. 2, in which modification two welts are used upon the outsides 50 of the joint, instead of one welt within the joint.

Referring now more particularly to the 55 drawing, wherein like characters of reference designate similar parts in all the figures, the numeral 1 denotes the upper strip of the collar body, and 2 the lower strip

of the same. The aperture formed by these two strips is denoted by the numeral 3, and is intended to be filled with packing material (not shown) in the usual manner. The outer edges of the strips 1 and 2 are brought together as indicated at 4, and a welt 5 is provided within the collar body upon the center of which the edges 4 meet, the upper and lower members of the body being secured to this welt by seams 6 and 7 respectively. The parts 1, 2, and 5 are further secured to each other by means of a lacing 8, the lace material preferably being a leather thong. A somewhat larger welt 9 is also provided upon the outside of the collar in such a manner as to cover the joint 4, the seam 6 being employed to attach it to the body member 1. If it be desired to secure this welt still more strongly in place, the lacing 8 may be passed through the part 9 as well as through the parts 1, 2 and 5.

Between the inner edges of the body members 1 and 2 is placed a welt 6^a, which also separates the longitudinal edges of the rim 80 10, the joints formed between the parts 1, 2, and 10 being denoted by the numeral 11. The aperture 12 within the rim will be filled with packing material as in the case of the collar body. The rim edges are secured to 85 the upper portion of the welt by a seam 13, and the inner edges of the body members 1 and 2 are attached to the lower portion of the welt by means of a seam 14. The parts 1, 2, 6^a, and 10 are further connected by a 90 lacing formed by a leather thong 15, which serves to form a very durable fastening between said parts.

A modification of the joint just described between the rim and the body of the collar 95 is illustrated in Fig. 4. In this form of the device, the welt 6^a is not employed, but in its stead, a pair of welts 16 are used, one being positioned upon each side of the joints 11. The seams 13 and 14 and the thong lacing 15 100 will be employed as before, being passed through both of the welts 16.

The use of a leather thong has been found to be most satisfactory for the purpose above described, but it would also be possible to use metal staples, or similar devices for the same purpose. It is also to be understood that while leather welts will be preferably used for the parts 5, 6^a, 9 and 16, webbing or other suitable material might 110 also be adapted to the purpose. Also it is obvious that the principle of the invention

would remain the same if either one of the 16
welts were dispensed with.

The use of the thongs 8 and 13 add
greatly to the strength of the joints in con- 5
junction with which these thongs are used.
The use of the thongs at the joint, which
connects the rim with the body of the collar,
is especially advantageous, since it makes
necessary a large hame room in order to
10 present sufficient of the edges of the body
and rim to produce a strong connection.
The hame, therefore, may be securely seat-
ed in this space or room thus provided, and
will be positively prevented from slipping
15 clear of the collar.

What we claim is:

1. In a horse collar, the combination of,
a body cover having its edges in contact and
flush, a row of stitches passing transversely
20 through said body cover edges and uniting
the same, a rim cover having its edges in
contact and flush, a row of stitches passing
transversely through the rim cover edges
and uniting them, the corresponding edges
25 of the body cover abutting and registering
with the corresponding edges of the rim
cover whereby the opposing portions of the
body and rim are alined, elongated welt
strips mounted upon the outer side of each
30 of the meeting portions of the covers and
extending laterally over the adjacent meeting
portions of the covers, the said rows of
stitches also passing transversely through
the longitudinal edge portions of the welt
35 strips, whereby the latter are united with
the covers, a thong laced through the covers
and welt strips and passing first through
welt strip and rim cover without contact
40 with the body cover and then passing
through the welt strips and body cover with-
out contact with the rim cover.

2. In a horse collar, a body cover having
its terminating edges in contact and sub-
stantially flush, a rim cover having its ter-
minating edges flush and in contact, the
45 flush edges of the body cover abutting the
flush edges of the rim cover, welt strips dis-
posed against the outer side of each cover
portion and overlapping onto the outer sides
50 of each cover at each side of the joint be-
tween the edges of the covers, two rows of
marginal stitches, each passing through the
welt strips and contacting edge portions of
one of the covers whereby one row of stitches
55 is located on one side of the joint between
the covers and the other row of stitches is
located on the other side of said joint, and
a thong laced through the covers and the
strips and around the joint, said thong

passing alternately through the strips and 60
rim cover and the strips and the body cover.

3. In a horse collar, a body cover having
its terminating edges in contact and sub-
stantially flush, a rim cover having its ter-
minating edges flush and in contact, the 65
flush edges of the body cover abutting the
flush edges of the rim cover, welt strips dis-
posed against the outer side of one of the
cover portions and overlapping onto the
70 outer sides of the other cover at each side of
the joint between the edges of the covers,
and a thong laced through the covers and
the strips and around the joint, said thong
passing alternately through the strips and
75 rim cover and the strip and the body cover.

4. In a horse collar, a body cover having
its terminating edges in contact and sub-
stantially flush, a rim cover having its ter-
minating edges flush and in contact, the
80 flush edges of the body cover abutting the
flush edges of the rim cover, welt strips dis-
posed on each side of the covers and over-
lapping at each side of the joint between
the edges of the covers, two rows of mar-
85 ginal stitches, each passing through the welt
strips and the edge portions of one of the
covers whereby a row of stitches is located
on each side of the joint between the covers,
and a thong laced through the covers and
90 the strips and around the joint between the
covers, said thong passing alternately
through the strips and the rim cover and
the strips and body cover.

5. In a horse collar, a body cover having
its terminating edges substantially flush, a 95
rim cover having its terminating edges sub-
stantially flush, the edges of one cover abut-
ting the edges of the other cover, a welt
strip superimposed upon the covers at the
joint therebetween and overlapping upon 100
each cover and secured thereto, both edge
portions of each cover being fastened in
connection with the welt strip, and a thong
lacing laced through the welt strip and the
105 four adjacent edge portions of the covers,
said thong being laced through the compo-
nent portions of one cover and the welt
strip without contacting with the component
portions of the other cover and the adjacent
portion of the strip. 110

In testimony whereof we have signed our
names to this specification in the presence of
two subscribing witnesses.
